APPARATUS FOR STABILIZING THE MOVEMENT OF OPPOSED PISTONS IN INTERNAL COMBUSTION ENGINES

Raul Pateras Pescara, Paris, France

Application January 5, 1933, Serial No. 650,351
In France March 17, 1932

16 Claims. (Cl. 230—56)

The present invention relates to methods and apparatus for stabilizing the return movement of opposed pistons in internal combustion engines of the type in which two compressing pistons are driven directly by internal combustion.

In motor compressors provided with opposed pistons of the type above referred to the pistons are subjected on their return stroke to the action of the compressed air cushion contained in a clearance space inside the compression chamber. It is obvious that the energy derived from the compressed air in this way for the return stroke, is proportional to the quantity of air remaining in the clearance space at the end of the piston's compression stroke i. e. that it varies directly with the length of the latter.

It has been previously indicated, in the inventor's prior Patent No. 1,732,693, issued October 22, 1929, that variations in the energy for the return stroke caused by variations in the length of the piston's motive stroke (which will hereafter be called compression stroke) may be compensated by providing additional closed clearance spaces containing air or an inert gas, the latter providing energy increasing in proportion to the length of the piston's compression stroke.

In actual practice, it is found that the compensation thus obtained is not always rigorous, since the energy furnished by the expansion of compressed air in the compression chamber in the course of the return stroke varies directly in proportion to the length of the piston's compression stroke, while the energy furnished by the compressed fluid functioning as compensator varies also with the length of the piston's compression stroke but in accordance with a more complicated thermo-dynamic law.

One of the objects of the present invention is to provide a method and apparatus for rigorously compensating variations in the length of the piston's compression stroke so that the piston always returns to the same point prior to each explosion.

Another object is to provide a single stage motor-compressor wherein compensation is obtained in the manner above indicated.

A further object is to provide a multiple stage motorcompressor acting to properly compensate variations in the length of the motive stroke.

Still further objects will appear in the course of the detailed description now to be given with reference to the accompanying drawings, wherein:

Fig. 1 is a diagrammatic section through a single-stage motorcompressor illustrating one possible embodiment of the invention;

Fig. 2 illustrates, in the same manner as Fig. 1, a second single stage motorcompressor assembly;

Fig. 3 shows a pair of diagrams representing the energy relations during the compression and return strokes of the piston and the same relations for the compensating auxiliaries;

Fig. 4 is a diagram showing the energy relations during compression, return and compression and for all of these combined;

Fig. 5 is a diagrammatic section through a two-stage motorcompressor embodying a second possible form of the invention;

Fig. 6 includes a pair of diagrams showing the energy relations during compression at each of the two stages;

Fig. 7 is a diagram showing the curves of variation in energy during the return stroke;

Fig. 8 illustrates in a manner similar to Fig. 5 a second form of two-stage motorcompressor; and

Fig. 9 represents, in diagrammatic section, a third two-stage motor-compressor.

Referring to Figure 1 of the drawings, there is shown one half of a motor compressor assembly of the opposed, aligned piston type described in the inventor's patent above referred to and composed of the following elements: a pair of staged pistons 1, 2, 3 mounted to move in aligned cylinders 9, 5 and 6 respectively, cylinder 9 forming part of the motor assembly, cylinder 5 part of the compressor assembly and cylinder 6 part of the compressed air compensating assembly: an air storage tank 7 containing air under constant pressure said tank communicating permanently with cylinder 6 and being provided with a take-off 11; an air inlet valve 8 operating to admit air from the atmosphere into cylinder 5 during part of the return stroke of piston 2; and a discharge valve 10 functioning to permit air under pressure in cylinder 5 to flow into reservoir 7.

The operation of the above described assembly will be better understood by referring to Figs. 3 and 4. In Figure 3, a—b represents the curve of air compression in cylinder 5, b—c the discharge of compressed air through valve 10 under constant pressure, c—d the curve for expansion of the air remaining in cylinder 5 at the end of the compression stroke and during the return stroke, and d—e the aspiration of air from the atmosphere into cylinder 5 via valve 8. Area c—d—e represents the energy furnished during the return stroke by the air confined in the clearance space of cylinder 5. This energy, which varies with the length of compression stroke b—c, is reduced to zero when the clearance space

becomes vanishingly small and becomes equal to the energy of compression when the discharge stroke $b-c$ is zero in length. The variation of this energy is represented by the straight line 5 $o-p$ in Figure 4.

Inspection of the left hand portion of Fig. 3 will show that the diagram of energy furnished by compensating cylinder 6 and the air under constant pressure in reservoir 7 may be represented by hatched rectangle $k-l-m-n$, the energy furnished by the air under constant pressure increasing in proportion to the length of the compression stroke. The variations in energy of the air cushion in cylinder 6 are represented in 10 Fig. 4 by straight line $r-s$ sloping in the opposite direction to line $o-p$. If the sections of pistons 2 and 3 and the volume of the clearance space of the cylinder 5 are properly chosen, the slopes of lines $o-p$ and $r-s$ may be made equal 15 and opposite, that is to say, their sum will be represented by a straight horizontal line passing through point r (in other words, cylinder 6 will 20 act to rigorously compensate deficiencies in return energy derived from the compressed air in cylinder 5) and the total return energy is always sufficient to bring back pistons 1 to the same 25 point irrespective of variations in the length of the compression stroke of said pistons.

In the variant illustrated in Fig. 2 hollow pistons 51, integral with pistons 52, slide in motor cylinder 53. Air is compressed in cylinders 54 supporting piston 52 and flows via a valve 63 into a passage 60 lying between (1) a first tube 56 slidably contacting with the interior wall or 30 cylinders inside hollow piston 51 and (2) a second tube 59 communicating at opposite extremities with reservoir 57 containing air under constant pressure and the cylinder 55 inside piston 51, whence the air discharges through tube 59 35 into reservoir 57 and through take-off 61 to the place of use. The air is aspirated from the atmosphere into cylinder 54 via valve 64. It will be seen that cylinder 55 inside piston 51 is the equivalent of cylinder 6 in Fig. 1 and that the two assemblies will operate substantially identically. In 40 this form of motor-compressor, the air driven out of compression chamber 54 and circulating through passage 60 serves to cool the piston assembly.

Reservoirs 7 and 57 in Figs. 1 and 2 may be provided with cooling systems of any desired type and cooled air for combustion may be led therefrom to motor cylinders 9.

Referring to Fig. 5 of the drawings, there is 55 shown an assembly similar in all respects to the one represented in Fig. 1, except that cylinder 6 is provided with inlet and exhaust valves 8¹ and 10¹ operative respectively to draw air from reservoir 7 and to deliver air via a conduit 12 to a high pressure air storage reservoir 15.

It will be readily understood that this form of apparatus differs from those illustrated in Figs. 1 and 2 only in being of the two-stage instead of the single stage type.

The cycle of this two stage motor-compressor is shown in Fig. 6, wherein the first stage of compression is represented by area A-B-C-D and the second stage by area F-G-H-I. These diagrams show the forces acting on the piston 65 as a function of the latter's position. The aspirating phase occurs during D-A and I-F, the compression phases during A-B and F-G, the return stroke between B-C and F-G, while expansion occurs between C-D and H-I.

If the dimensions of cylinders 5 and 6 are

properly chosen, the compression portions of the diagrams during each of the two stages may be made superposable. The energy for the return stroke of pistons 1, 2, 3 is the sum of expansion phases C-D-E and H-I-J-M plus the energy 5 derived from the pressure exerted on piston 3 by the air in the low pressure reservoir 7, this latter energy being represented by rectangle I-F-N-J, since the air is at constant pressure. Inasmuch as the energy derived from areas 10 C-D-E and H-I-L varies linearly with the length of the compression stroke, their sum will be represented by a straight line O-P (Fig. 7). As already indicated in connection with the descriptions of Figs. 1, 3 and 4, the work effected 15 by the compressed air in cylinder 6 will take the form of a straight line R-S sloping in the opposite direction to line O-P. Assuming the clearance spaces and the dimensions of cylinders 5 and the pressures existing therein to be properly 20 chosen the slopes of lines O-P and R-S may be made exactly equal and opposite and their sum will yield a straight horizontal line R-V corresponding to an energy sufficient to insure the return stroke of the pistons. In other words, as 25 in the case of Fig. 1, the return stroke of the piston will be exactly compensated whatever be the length of the compression stroke.

In theory, exact compensation should be obtained only when the pressures in reservoirs 7 30 and 57 have a predetermined value. But in practice, it is found that when the dimensions of the various operating elements are properly chosen, the pressures in cylinder 5 may be given a certain range of values.

As will be obvious to those skilled in the art, the invention is not to be taken as limited to a combination of only two stages. Obviously the number of stages may be multiplied in accordance with the pressure of air desired.

When two-stage motor-compressors are used, it is sometimes necessary to considerably increase the clearance space in the compressor portions in order to obtain sufficient energy for a proper return stroke. This increases the size of the machine to a degree which may become undesirable. In order to reduce the size of the machine, an assembly such as that shown in Fig. 8 may be employed. Here, piston 43 is provided with a hollow cylindrical portion 16 receiving a fixed 50 tube 17 air from high pressure air storage reservoir 47 passed through an opening 18 into tube 17 and cylinder 16 so as to increase the energy available for a return stroke. By increasing the diameter of hollow cylinder 16, the energy for the 55 return may be increased as desired.

Fig. 9 shows a similar assembly for increasing the energy of the return stroke without increasing the volume of the clearance spaces. This assembly differs from the one shown in Fig. 8 60 only in that a second fixed tube 59 is inserted inside fixed tube 17 (see also Fig. 2), the air traversing valve 18¹ moving first through a passage 20 into cylinder 16 before passing out through passage 18¹ into reservoir 15, thus cooling the inside of piston 7.

From the foregoing, it will be seen that substantially rigorous compensation is obtained in motor-compressor of the type described, utilizing either single or multiple stages of compression. At the same time, a supply of cooling air is provided for the motor pistons and cylinders.

In the claims, the term "rigidly connected" applied to the pistons should be interpreted to include the case where the latter are integral with 70 75

- one another. The pistons and cylinders forming part of the motor compressing and compensating assemblies will be distinguished by applying the same terms thereto.
5. What I claim is:—
1. In combination in an internal combustion motor-compressor unit, motor and compressor pistons, motor and compressing cylinders co-acting with said pistons, said compressing cylinder including a clearance space adapted to contain residual air under pressure acting as a cushion to return said compressor piston,—a compensating assembly including a source of fluid under substantially constant pressure and means for conducting said fluid under constant pressure to a point where it reacts on said compressor piston to supplement the action of the air cushion in said clearance space.
  2. A structure as defined in claim 1 in combination with valve means operative to conduct air from said compressing cylinder to said source of fluid pressure.
  3. A structure as defined in claim 1 in combination with means for conducting air from said compressing cylinder to said source of fluid under constant pressure and means for cooling the air in said source.
  4. In combination in an internal combustion motor-compressor unit, a motor piston, a motor cylinder supporting said motor piston, a compressing cylinder mounted in line with said motor cylinder and including a clearance space adapted to contain residual air, and a compressor piston integral with said motor piston and slidably mounted in said compressing cylinder,—a compensating assembly including a source of fluid under constant pressure reacting on said motor piston and said compressor piston in the direction of their return stroke.
  5. In combination in an internal combustion motor-compressor unit, a motor piston, a motor cylinder supporting said piston, a compressing cylinder mounted in line with said motor cylinder and including a clearance space adapted to contain residual air, and a compressor piston integral with said motor piston and slidably mounted in said compressing cylinder,—a compensating assembly including a compensating piston rigidly attached to said motor and compressor pistons, a cylinder mounted to slidably receive said compensating piston and means for introducing a fluid under constant pressure into said last-named cylinder.
  6. In combination in an internal combustion motor-compressor unit, a motor piston, a motor cylinder supporting said piston, a compressing cylinder mounted in line with said motor cylinder and including a clearance space adapted to contain residual air, and a compressor piston rigidly connected to said motor piston and slidably mounted in said compressing cylinder,—a compensating assembly including a compensating piston rigidly attached to said motor and compressor pistons, a cylinder mounted to slidably receive said compensating piston, and a reservoir mounted to receive compressed air from said compressor cylinder and deliver air to said compensating cylinder.
  7. A structure as defined in claim 6 in combination with valve means controlling the ingress of air from said reservoir to said compensating cylinder, a second reservoir mounted to receive air from said compensating cylinder and a valve controlling communication between said compensating cylinder and said second reservoir.
  8. In combination in an internal combustion motor-compressor unit, a motor piston, a motor cylinder supporting said piston, a compressing cylinder mounted in line with said motor cylinder and including a clearance space adapted to contain residual air,—a compressor piston rigidly connected to said motor piston and having a hollow portion formed therein, said compressor piston being slidably mounted in said air compressing cylinder, a fixed tube mounted inside the hollow portion of said compressor piston, and means for supplying air under constant pressure to said fixed tube.
  9. In combination in an internal combustion motor-compressor unit, a motor piston, a motor cylinder supporting said piston, and a compressing cylinder mounted in line with said motor cylinder and including a clearance space adapted to contain residual air,—a compressor piston rigidly connected to said motor piston and having a hollow portion formed therein, said compressor piston being slidably mounted in said compressing cylinder, a fixed tube mounted inside the hollow portions of said compressor piston, and a reservoir adapted to contain a fluid under constant pressure and communicating with the interior of said hollow tube.
  10. A structure as defined in claim 9 in combination with a third cylinder mounted in line with said motor and compressing cylinder, a hollow compensating piston rigidly connected to said compressor piston and slidably mounted in said third cylinder, the hollow portion of said compensating piston enclosing said fixed tube, and means including a valve operative to establish communication between said reservoir and said third cylinder.
  11. In combination in an internal combustion motor-compressor unit, motor and compressor pistons, motor and compressing cylinders co-acting with said pistons, said compressing cylinder including a clearance space adapted to contain residual air under pressure acting as a cushion to return said pistons,—a compensating assembly including a source of fluid under constant pressure and means for conducting said fluid under constant pressure to a point where it reacts on said pistons to supplement the action of the air cushion in said clearance space, the dimensions of said motor and air compressing cylinders and the pressure from said source being chosen so that said source of fluid under constant pressure acts to supplement the expansion of the air in said clearance spaces during a return stroke to bring said motor piston back to the same point irrespective of the length of the compression stroke.
  12. In combination in an internal combustion motor-compressor unit, freely movable motor and compressor pistons, motor and compressing cylinders coacting with said pistons, said compressing cylinder including a clearance space adapted to contain residual air under pressure acting as a cushion to return said pistons, said unit including a space of variable volume separate from said compressing cylinder, and means for supplying to said space a fluid under a pressure which is dependent on the compression pressure of the compressing cylinder whereby said fluid reacts on said pistons to supplement the action of the air cushion in said clearance space, the dimensions of said cylinders and the size of said space being chosen so that said fluid acts to supplement the expansion of air in said clearance space.

ance space during a return stroke to bring said motor piston back to the same point irrespective of the length of the compression stroke.

13. In a device as claimed in claim 12, a tube 5 for conducting away the air compressed by said unit, said space communicating with said tube.

14. In combination in an internal combustion motor-compressor unit, a motor piston and a plurality of compressor pistons, a motor cylinder and a plurality of compressing cylinders co-acting with said pistons, said compressing cylinders including clearance spaces adapted to contain bodies of residual air under pressure acting as cushions to return said pistons, a reservoir 10 connected between said compressing cylinders, a second reservoir connected to said compressing cylinders, said unit including a space separate from said compressing cylinders and connected to said second reservoir whereby the air contained in said second reservoir reacts on said pistons to supplement 15 the action of the air cushions in said clearance spaces and the air in said first reservoir.

15. In combination in an internal combustion motor-compressor unit, a motor piston and a plurality of compressor pistons, a motor cylinder and a plurality of compressing cylinders co-acting with said pistons, said compressing cylinders including clearance spaces adapted to contain bodies of residual air under pressure acting as cushions to return said pistons, a reservoir 10 connected between said compressing cylinders, a second reservoir connected to said compressing cylinders, said unit including a space separate from said compressing cylinders and connected to said second reservoir whereby the air contained in said second reservoir reacts on said pistons to supplement 15 the action of the air cushions in said clearance spaces and the air in said first reservoir.

20. In combination in an internal combustion motor-compressor unit, a motor piston and a plurality of compressor pistons, a motor cylinder and a plurality of compressing cylinders co-acting with said pistons, said compressing cylinders including clearance spaces adapted to contain bodies of residual air under pressure acting as cushions to return said pistons, a reservoir 20 connected between said compressing cylinders, a second reservoir connected to said compressing cylinders, said unit including a space separate from said compressing cylinders and connected to said second reservoir whereby the air contained in said second reservoir reacts on said pistons to supplement 25 the action of the air cushions in said clearance spaces and the air in said first reservoir.

25. In combination in an internal combustion motor-compressor unit, a motor piston and a plurality of compressor pistons, a motor cylinder and a plurality of compressing cylinders co-acting with said pistons, said compressing cylinders including clearance spaces adapted to contain bodies of residual air under pressure acting as cushions to return said pistons, a reservoir 25 connected between said compressing cylinders, a second reservoir connected to said compressing cylinders, said unit including a space separate from said compressing cylinders and connected to said second reservoir whereby the air contained in said second reservoir reacts on said pistons to supplement the action of the air cushions in said clearance spaces and the air in said first reservoir.

15. In combination in an internal combustion motor-compressor unit, a motor piston and a plurality of compressor pistons, a motor cylinder and a plurality of compressing cylinders co-acting with said pistons, said compressing cylinders including clearance spaces adapted to contain bodies of residual air under pressure acting as cushions to return said pistons, a reservoir 10 connected between said compressing cylinders, a second reservoir connected to said compressing cylinders, said unit including a space separate from said compressing cylinders and connected to said second reservoir whereby the air contained in said second reservoir reacts on said pistons to supplement 15 the action of the air cushions in said clearance spaces and the air in said first reservoir.

16. In combination in an internal combustion motor-compressor unit, a motor piston and a plurality of compressor pistons, a motor cylinder and a plurality of compressing cylinders co-acting with said pistons, said compressing cylinders including clearance spaces adapted to contain bodies of residual air under pressure acting as cushions to return said pistons, a reservoir 10 connected between said compressing cylinders, a second reservoir connected to said compressing cylinders, said unit including a space separate from said compressing cylinders and connected to said second reservoir whereby the air contained in said second reservoir reacts on said pistons to supplement 15 the action of the air cushions in said clearance spaces and the air in said first reservoir.

16. In combination in an internal combustion motor-compressor unit, motor and compressor pistons, motor and compressing cylinders co-acting with said pistons, said motor and compressor pistons having a space therein open at the end remote from the motor cylinder, a reservoir, a tube connected to said reservoir and extending through said open end into said space 20 to a point adjacent the inner end thereof, and means to connect said compressing cylinder to said space, the pressure in said space acting to return the pistons, said tube causing the air to flow through the space so as to cool the pistons.

RAUL PATERAS PESCARA.
